UNITED STATES PATENT OFFICE.

WILLIAM GORDON, OF NEW YORK, N. Y.

DESIGN FOR A CIGAR LIGHTER.

Application filed January 10, 1929. Serial No. 29,563. Term of patent 3½ years.

To all whom it may concern:

Be it known that I, WILLIAM GORDON, a citizen of the United States, residing at the borough of Manhattan, in the city, county, and State of New York, have invented a new, original, and ornamental Design for Cigar Lighters, of which the following is the specification, reference being had to the accompanying drawing, forming part thereof.

The figure is a perspective view of a cigar lighter, showing my new design.

I claim:—

The ornamental design for a cigar lighter as shown.

WILLIAM GORDON.
